UNITED STATES PATENT OFFICE.

EMIL LAMPRECHT, OF PHILADELPHIA, PENNSYLVANIA.

CUE-TIP.

971,201.

Specification of Letters Patent. Patented Sept. 27, 1910.

Application filed December 6, 1909. Serial No. 531,663.

To all whom it may concern:

Be it known that I, EMIL LAMPRECHT, a citizen of the United States, residing at Philadelphia, in the county of Philadelphia and State of Pennsylvania, have invented 5 certain new and useful Improvements in Cue-Tips, of which the following is a specification.

My invention relates to improvements in 10 cue tips, and more particularly to an improved, removable tip which can be quickly removed from the cue and replaced by another whenever desired.

A further object is to provide an improved 15 construction of removable cue tip in combination with a coöperating part in the cue, which enables a player to select any cue that suits him, and then any tip that suits him, and place the two in locked relation to each 20 other, and which also enables him, at any time during the course of the game, to change from one tip to another in order to make particular shots.

A further object is to provide an improved 25 removable cue tip, which when in a position against the end of a cue, will be firmly held against rotary, as well as longitudinal, movement, but which can be quickly removed when desired.

With these and other objects in view the 30 invention consists in certain novel features of construction and combinations and arrangements of parts as will be more fully hereinafter described and pointed out in 35 the claims.

In the accompanying drawings: Figure 1 is a fragmentary view in longitudinal section illustrating my improved tip secured to the end of a cue. Fig. 2 is a perspective 40 view of one form of my improved tip in course of construction. Fig. 3 is a view of the tip shown in Fig. 2, when the structure is completed. Figs. 4 and 5 are views similar to Figs. 2 and 3, but illustrating a 45 slightly modified structure, and Fig. 6 is a perspective view of the sleeve or bushing 3.

1 represents a cue having a longitudinal bore 2 at its smaller end, in which a metal sleeve or bushing 3 is forced into the bore 50 and by friction, and for all practical purposes permanently secured, said sleeve or bushing being shorter than the bore, the outer end of the bushing lying flush with the end of the cue, while the inner end of

the bushing is spaced an appreciable distance from the inner end of the bore.

My improved tip, which may of course be made of various materials, is preferably made in two parts, 4 and 5, cemented together, the outer part 4 being rounded and shaped in various ways, according to the trade, and the inner member 5, constituting a disk having a flat inner face to bear against the end of the cue. This disk 5 is made with a slot 6, the end walls of which 60 at the inner face of the disk, are made with longitudinal recesses 7, to receive the outwardly bent ends 8 of my improved spring wire member 9.

The member 9 is composed of a single 70 piece of spring wire, which is coiled midway between its ends as shown at 10, and the extreme ends of the wires are bent outward as shown at 8 so that when the approximately parallel members 11, 11 of the spring 75 wire are pressed toward each other, the ends of the wire may be inserted in slot 6, and when the members 11, 11 are released, they will spring apart, projecting the bent portions 8 into recesses 7. While in this position a cylindrical shank 12, which may of course be of various materials as for example, metal, hard rubber, etc., is molded around the members 11, 11 inclosing them throughout a portion of their length, and 80 said material constituting the shank will find its way into the slot 6, as shown most clearly in Fig. 1, and prevent any possibility of the bent ends 8 escaping from recesses 7. On shank 12, a lug or key 13 is 85 formed, which is adapted, when the shank is inserted in the sleeve or bushing 3, to enter a notch 14 in said sleeve or bushing, to prevent any rotary movement of the tip with 90 relation to the cue. In the structure shown 95 in Figs. 1, 2, and 3, the coiled portion 10 is flattened, and when bent apart as shown in Fig. 3, two spring jaws are formed which are adapted to engage over the inner edge of the sleeve or bushing 3, to hold the tip 100 against the cue. As shown in Figs. 4 and 5, the coils may be circular if desired, and I do not therefore, limit myself to any particular shape of such coils, nor to any particular manner of forming these spring jaws 105 which engage over the inner end of the sleeve or bushing.

In operation, with the parts as shown in

Fig. 1, to remove the tip, it is simply necessary to exert sufficient pull on the tip to overcome the engagement of the jaws 10 against the inner end of sleeve or bushing 3 and pull said jaws through the sleeve, it being noted that longitudinally of jaws, or rather transversely of the tip, these jaws are longer than the diameter of sleeve or bushing 3, so that when being drawn through the bushing they will be compressed, and when free from the bushing will expand. When a new tip, or the same tip, is inserted in the cue, this action also takes place; namely compressing the jaws or coiled portions 10, so that when the tip is pressed in tight against the end of the cue with the lug or key 13 in notch 14, the jaws will be in a position to spring out and engage over the inner edge of sleeve or bushing 3, and securely hold the tip against the end of the cue, the key 13 holding the tip against any rotary movement, which would interfere with the proper chalking of the cue, as well as the proper operation of the cue, and the members or jaws 10 will hold the tip tight against the end of the cue, and maintain it in this position until a sufficient pull is applied on the tip to overcome the spring action of said jaws.

By means of my improvements, when applied to cues, a great deal of the expense and trouble at present incurred by the proprietors of pool and billiard halls will be overcome. One of the greatest sources of expense is that of replacing tips which have been broken from the cues, and then another great source of trouble is to get a cue which will just suit a player, and combine therewith a tip which will just suit the same player, and it frequently happens that in the course of a game a player desires to use more than one style of tip. With my improvements all of these objections are overcome. A player may secure a cue that suits him, may place in this cue a tip that suits him, and may change this tip whenever he desires for another, according to the play he desires to make. When a tip becomes broken, there is no expense whatever attached to the replacing of the same, except the cost of the tip itself, as there is no skilled labor required in this work.

Various slight changes might be made in the general form and arrangement of parts described without departing from my invention, and hence I do not restrict myself to the precise details set forth, but consider myself at liberty to make such changes and alterations as fairly fall within the spirit and scope of the appended claims.

Having thus described my invention what I claim as new and desire to secure by Letters Patent is:—

1. A cue tip comprising a ball engaging member, a spring wire coiled between its

ends and having its ends secured to said ball engaging member, and a shank molded around the end portions of said wire, and forming a cylindrical portion to be forced into a cue.

2. A cue tip, comprising a ball engaging member having a slot therein, a spring wire coiled between its ends and secured at its ends in said slot, and said coiled portion of the wire flared apart, forming spring jaws adapted to engage over an internal shoulder 75 in the bore of a cue.

3. A cue tip comprising a ball engaging member having a slot therein, a spring wire coiled between its ends and bent outward 80 at its ends and positioned at its ends in said slot, a shank molded around said spring wire and said coiled portion of said spring wire bent apart, forming spring jaws adapted to engage behind an internal shoulder in 85 the bore of a cue.

4. The combination with a cue having a longitudinal bore in its end, and a sleeve or bushing fixed in said bore and terminating short of the inner end of the bore, of a tip, 90 and spring jaws on said tip adapted to be moved through said sleeve or bushing and spring outward in engagement with the inner end of said sleeve or bushing.

5. The combination with a cue having a 95 longitudinal bore in its end and a sleeve or bushing fixed in said bore and terminating short of the inner end of the bore, a tip adapted to be positioned against the end of the cue, a shank on said tip adapted to be 100 positioned in said sleeve, and means on said shank adapted to engage over the inner end of said sleeve.

6. The combination with a cue having a longitudinal bore in its end and a sleeve or 105 bushing fixed in said bore and terminating short of the inner end of the bore, of a tip adapted to be positioned against the end of the cue, a shank on said tip adapted to be positioned in the sleeve and spring jaws 110 adapted to engage over the inner end of said sleeve or bushing.

7. The combination with a cue having a longitudinal bore in its end and a sleeve or bushing fixed in said bore terminating at 115 its inner end short of the inner end of the bore and having a notch at its outer end, a tip adapted to be positioned against the end of the cue, a shank on said tip adapted to be positioned in said sleeve or bushing, a 120 lug or key on said shank adapted to be positioned in the notch in the sleeve or bushing, and spring wire jaws fixed to said shank and adapted to engage over the inner end of said sleeve or bushing.

8. The combination with a cue having a longitudinal bore in its end, and a sleeve or bushing fixed in said bore terminating at its inner end short of the inner end of the bore and having a notch at its outer end, of a 130

tip comprising two members secured together, one member adapted to be positioned against the end of the cue and having a slot therein, a spring wire coiled between 5 its ends forming spring jaws, and bent outward at its ends positioned in said slot, a shank cast on said tip inclosing a portion of said spring wires and projecting into the slot, a lug or key on said shank adapted to 10 enter the notch in the sleeve or bushing, and

said spring jaws adapted to engage over the inner end of the sleeve, substantially as set forth.

In testimony whereof I have signed my name to this specification in the presence of 15 two subscribing witnesses.

EMIL LAMPRECHT.
